CLAIM

The ornamental design for a flexible flashlight, as shown and described.

DESCRIPTION

FIG. 1 is a front perspective view of a flexible flashlight, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is the front perspective view of the flexible flashlight, shown in use.

The broken lines shown in the drawings depict portions of the flexible flashlight that form no part of the claimed design.
